UNITED STATES PATENT OFFICE.

PETER J. OTTO, OF LANCASTER, PENNSYLVANIA.

DESIGN FOR HONEY-COMB COVERLETS.

Specification forming part of Design No. **7,499**, dated June 23, 1874; application filed June 9, 1874.
[Term of Patent 14 years]

To all whom it may concern:

Be it known that I, PETER J. OTTO, of the city of Lancaster, in the State of Pennsylvania, have invented a Design for Weaving Honey-Comb Coverlets, of which the following is a specification:

The nature of my design is fully represented in the accompanying photographic illustration.

The border of the quilt is woven as honey-comb, and the figures are parallelograms A at the sides, and squares A' at the corners. The central figure is an ornamental tweel or honey-comb figure surrounded by honey-comb band C.

I do not desire to limit myself to the configuration of this central figure, for I consider myself the first to weave a quilt with a honey-comb border and central tweed figure, or what is termed a one-bodied honey-comb quilt.

I claim—

The design for a quilt, consisting of the honey-comb band C and central figure, as shown and described.

P. J. OTTO.
